UNITED STATES PATENT OFFICE.

CHARLES E. CUNNIUS, OF FREELAND, PENNSYLVANIA.

WRENCH.

No. 804,831.

Specification of Letters Patent.

Patented Nov. 21, 1905.

Application filed July 17, 1905, Serial No. 270,029.

To all whom it may concern:

Be it known that I, CHARLES E. CUNNIUS, a citizen of the United States, residing at Freeland, in the county of Luzerne and State 5 of Pennsylvania, have invented a new and useful Wrench, of which the following is a specification.

My invention relates to wrenches, and while especially useful and desirable as a 10 pipe-wrench may be used with satisfactory results for any other purpose for which a wrench is ordinarily used.

It is well known that in the use of pipe-wrenches the wrench will be used sometimes 15 for many successive days upon the same sized pipe, and when the desired adjustment has been secured it is desirable to maintain such adjustment so long as the wrench is being used upon the same size of pipe.

20 It is the object of my invention to provide a wrench which may be adjusted to any desired size of work-receiving opening and when so adjusted will remain set until the adjustment is intentionally changed.

25 With this and other objects in view the present invention consists in the combination and arrangement of parts, as will be hereinafter fully described, shown in the accompanying drawings, and particularly pointed 30 out in the appended claims, it being understood that changes in form, proportion, size, and minor details may be resorted to without departing from the spirit or sacrificing any of its advantages.

35 In the accompanying drawings, Figure 1 is a perspective view of my improved wrench. Fig. 2 is a longitudinal sectional view of my improved wrench. Fig. 3 is a transverse sectional view of my improved wrench, taken on 40 line 3 3 of Fig. 2. Fig. 4 is a perspective view of the latch of my improved wrench.

Like characters of reference designate corresponding parts throughout the several views.

45 My improved wrench comprises an elongated rigid handle member 1, having one end formed into a transversely-disposed work-engaging face 2. Upon the handle 1 and adjacent the face 2 is pivoted the block 3 by 50 means of the pivot-pin 4. The block 3 is provided with a longitudinal screw-threaded opening 5. A jaw member 6 is provided with a work-engaging face 7, arranged for co-operation with the face 2, and is formed integral 55 with the screw-threaded shank 8. The shank

8 has its threads interrupted by flattening its sides to form two parallel surfaces 9.

Upon the block is pivoted the latch member 10 by means of the arms 11 and the pivot-pin 12. The latch is provided with the angularly-disposed arms 13 and 14, arranged and proportioned to clamp the parallel sides 60 of the shank and prevent rotary displacement.

The operation of my improved wrench is 65 as follows: The latch 10 is disengaged from the shank and the jaw 6 rotated in either direction until the desired work-receiving aperture is obtained, after which the latch is clamped about the shank, which will prevent 70 rotary displacement and change of adjustment of the jaw until intentionally released.

Having thus described the invention, what is claimed is—

1. A wrench comprising a handle provided 75 with a work-engaging face, a block pivoted upon the handle, a jaw member having a shank passing through the block and a latch carried by the block and arranged to embrace the shank.

2. A wrench comprising a handle provided with a transversely-disposed work-engaging face, a block pivoted upon the handle, a jaw member having a shank passing through the block and a latch carried by the block and 80 arranged to embrace the shank.

3. A wrench comprising a handle provided with a work-engaging face, a block pivoted upon the handle, a jaw member having a shank passing through the block and a latch 85 pivoted to the block and arranged to embrace the shank.

4. A wrench comprising a handle, provided with a work-engaging face, a block pivoted upon the handle and provided with an opening, a jaw member having a shank passing through the block and provided with parallel sides, a latch pivoted upon the block and provided with a bifurcated clamp member arranged to clamp upon opposite parallel 95 sides of the shank.

5. A wrench comprising a handle provided with a transversely-disposed work-engaging face, a block pivoted upon the handle and provided with an opening, a jaw member 105 provided with a work-engaging face and a shank having angular sides and disposed within the opening of the block and a latch member pivoted to the block and having a bifurcated angular portion arranged to 110

clamp upon the parallel sides of the jaw-shank.

6. A wrench comprising a handle provided with a transverse work-engaging face, a block pivoted to the handle and provided with a screw-threaded opening, a jaw member provided with a screw-threaded shank with parallel flattened sides interrupting the screw-thread and engaged within the screw-threaded opening of the block and means to latch the jaw-shank against a rotary displacement.

7. A wrench comprising a handle provided with a transverse work-engaging face, a block pivoted to the handle and provided with a longitudinal screw-threaded opening, a jaw member having a work-engaging face

and provided with a screw-threaded shank with parallel flattened sides interrupting the screw-threads and engaged within the screw-threaded opening of the block, a latch member pivoted to the block and provided with an angularly-disposed bifurcated portion arranged to clasp the parallel sides of the jaw-shank to prevent rotary displacement of the jaw.

In testimony that I claim the foregoing as my own I have hereto affixed my signature in the presence of two witnesses.

CHAS. E. CUNNIUS.
